UNITED STATES PATENT OFFICE

2,499,468

ROTARY PHOTOPRINT WASHER

Michael A. Dodson, Long Beach, Calif.

Application July 16, 1946, Serial No. 683,899

4 Claims. (Cl. 95—93)

1

This invention relates to a washer for photographic prints and an object of my invention is to provide a device of this character which will effectively wash these prints by circulating water through the device, and also moving the container in which the prints are placed, while the water is circulating therethrough.

An object of my invention is to provide a photo print washer in which the incoming water serves to act as a motivating force for the basket containing the prints.

Another object is to provide a novel photo print washer in which the incoming water will spray into the basket containing the prints and will thus agitate the same and will cause a stream of clear water to flow around the prints at all times.

Still another object is to provide a novel photo print washer which is simple in construction, effective in operation and inexpensive to manufacture.

Other objects, advantages and features of invention may appear from the accompanying drawing, the subjoined detailed description and the appended claims.

In the drawing:

Figure 1 is a top plan view of the tub and the rotor.

Figure 2 is a transverse sectional view of my photo print washer.

Figure 3 is an enlarged fragmentary transverse sectional view of my photo print washer.

Referring more particularly to the drawing, the numeral 1 indicates a tub which is preferably cylindrical in form. The tub is provided with a water drain or outlet 2, adjacent its upper edge. A drain cock 3 is also provided adjacent the bottom of the tub so that it can be completely drained if desired.

A driving element 4 consisting of a spider is journaled in the bottom of the tub 1 and consists of a plurality of radial arms 5. In the bottom of the tub 1, I provide a plurality of fixed radial baffles 6. Each of the arms 5 are provided with a plurality of jet openings 7, through which water is jettisoned against the baffles 6. The reactive force of these jets against the arms 5 will cause the entire spider 4 to rotate. Water under usual city main pressure is introduced into the spider 4 through the pipe 8. The radial baffles 6, also prevent excessive turbulence of the water.

A basket 9 is formed with a solid floor 10 and the side walls are formed of wire or suitable foraminated material. On the outer ends of each of the arms 5, I provide a vertical stand pipe 11, and each of these stand pipes extends through

2

the floor 10, and are further provided with one or more ports 12, which further agitate the water within the basket, and cause an effective flow of water over the photographic prints. The basket 9 is readily removable when necessary by simply lifting it off the stand pipes 11.

Having described my invention, I claim:

1. A photo print washer comprising a tub, a spider rotatably mounted within the tub and spaced above the bottom of the tub, a water inlet extending into the spider, said spider including a plurality of radially extending arms, said arms each having a water outlet opening therein, a plurality of fixed radial baffles projecting upwardly from the bottom of the tub, said outlet openings being arranged in the bottom of said spiders to direct water downwardly and outwardly to impinge on the baffles, and a basket removably mounted on said spider and rotatable therewith.
2. A photo print washer comprising a tub, a spider rotatably mounted within the tub and spaced above the bottom of the tub, a water inlet extending into the spider, said spider including a plurality of radially extending arms, said arms each having a water outlet opening therein, a plurality of fixed radial baffles projecting upwardly from the bottom of the tub, the water from said outlet openings being arranged in the bottom of said spiders to direct water downwardly and outwardly to impinge on the baffles, and a basket removably mounted on said spider and rotatable therewith, a standpipe rising from each arm of said spider and extending into the basket, said stand pipe having a water outlet port therein, directing water into the basket.
3. A photo print washer, comprising a tub, a spider rotatably mounted in said tub and spaced above the bottom of the tub, a water intake pipe extending into said spider, said spider including a plurality of radial arms, each of said arms having water outlet openings therein, a plurality of fixed radial baffles in the bottom of said tub and projecting upwardly therefrom, said water outlet openings being arranged in the bottom of said arms and directing water downwardly and outwardly against the baffles, a drain in the side of said tub, and a basket removably mounted on said spider.
4. A photo print washer, comprising a tub, a spider rotatably mounted in the bottom of said tub and spaced above the bottom of the tub, a water intake pipe extending into said spider, said spider including a plurality of radial arms, each of said arms having water outlet openings therein, a plurality of fixed radial baffles in the bottom of said tub and projecting upwardly therefrom, said water outlet openings being arranged in the bottom of said arms and directing water downwardly and outwardly against the baffles, a drain in the side of said tub, and a basket removably mounted on said spider.
5. A photo print washer, comprising a tub, a spider rotatably mounted in the bottom of said tub and spaced above the bottom of the tub, a water intake pipe extending into said spider, said spider including a plurality of radial arms, each of said arms having water outlet openings therein, a plurality of fixed radial baffles in the bottom of said tub and projecting upwardly therefrom, said water outlet openings being arranged in the bottom of said arms and directing water downwardly and outwardly against the baffles, a drain in the side of said tub, and a basket removably mounted on said spider.

of said tub, said outlet openings being arranged in the bottom of said arms and directing water downwardly and outwardly against the baffles, a drain in the side of said tub, and a basket removably mounted on said spider, a stand pipe on the outer end of each of said arms, said stand pipes protruding into said basket through the floor thereof, and each of said stand pipes having a water outlet port therein, directing water into the basket.
